UNITED STATES PATENT OFFICE.

WILLIAM E. PARKER, OF NEW BRITAIN, CONNECTICUT, ASSIGNOR TO THE RUSSELL & ERWIN MANUFACTURING COMPANY, OF SAME PLACE.

DOOR-KNOB ROSE.

SPECIFICATION forming part of Letters Patent No. 653,693, dated July 17, 1900.

Application filed March 3, 1900. Serial No. 7,164. (No model.)

To all whom it may concern:

Be it known that I, WILLIAM E. PARKER, a citizen of the United States, residing in New Britain, in the county of Hartford and State of Connecticut, have invented a new and useful Improvement in Door-Knob Roses, of which the following is a specification, reference being had to the accompanying drawings, forming a part thereof.

10 My invention relates to improvements in knob-roses; and the main object of my improvement is to provide a hollow or raised-up sheet-metal rose-plate with an internal support adjacent to the knob-spindle.

15 In the accompanying drawings, Figure 1 is a front elevation of my knob-rose having a combined rose and escutcheon plate. Fig. 2 is a rear elevation of the upper part of the same. Fig. 3 is a horizontal section thereof 20 on the line *xx* of Fig. 1, and Fig. 4 is a front elevation of my knob-rose with a rose-plate substituted for the combined rose and escutcheon plate.

The combined rose and escutcheon plate 5 25 is formed of comparatively-thin sheet metal struck up in dies, so as to elevate or project its central portion 6 and form what I term a "hollow" back. This plate may be of any desired contour and is provided with screw-holes 7 30 for use in securing the plate to a door. I prefer to force the metal inwardly around the screw-holes in an old and well-known manner. An ordinary keyhole 8 is formed at the proper point in the plate 5, and a round hole 9, 35 Fig. 2, is formed in the said plate to receive the knob-rose center 10. I form the said rose-center of sheet metal, with its front of the desired diameter to receive the end of the knob-shank and with a circular boss 11 on its back, 40 the said boss being of a diameter to be received in the hole 9.

In order to support the rose-plate against the endwise pressure of the knob-shank and prevent the metal at the middle portion of the 45 plate from being crushed in toward the door, I secure the flanged supporting-ring 12 within the hollow back of the plate 5 immediately back of the rose-center. The supporting-ring is formed of sheet metal of sufficient thickness 50 to resist such endwise pressure as will ordinarily be exerted on the knob-shank, and it is struck up into what may be called "cup-

shaped," with a border flange and with a central hole of a size to receive the circular boss 11 of the rose-center 10. The depth of the 55 supporting-ring—that is, its dimension from front to rear—is equal to the depth of the depression on the back of the plate 5. The circular boss 11 is of a cylindrical form when first made, and it is passed through the round 60 hole 9 in the plate 5 from the front, after which the supporting-ring 12 is placed over the said boss 11 from the back of the said plate, and the outer end of the boss 11 is turned over to secure the said parts firmly 65 together, as shown in Fig. 3.

It will readily be seen that the rear face of the flanged supporting-ring 12 is in the same plane as the rear of the plate 5 at its edges, so as to rest against the surface of the door 70 to which the rose may be applied. The rear face of the said ring is broad enough to form a firm bearing that cannot be compressed into the surface of the wood, and the depth of the ring 12 from front to rear is such as to prevent the middle portion of the plate 5 from being depressed or bent out of place. I am thus enabled to construct the plate 5 of thin metal and connect the same with the rose-center in an inexpensive manner, and at the same time 80 the said thin-metal plate is firmly supported and may be cheaply given any desired ornamental form or design.

In Fig. 4 the plate 5^a is designed for a rose-plate only instead of a combined rose and escutcheon plate, as in the preceding figures. It has the same rose-center 10, secured in the manner and by the means hereinbefore described.

I claim as my invention—

The combination of the struck-up sheet-metal rose-plate having an elevated plate-like middle portion that forms a hollow back, with the rose-center on the front of the said plate, and the supporting-ring on the rear thereof 95 for supporting the middle portion of the said sheet-metal rose-plate against the endwise pressure of the knob-shank, substantially as described.

WILLIAM E. PARKER.
